GEORGE S. LEWIS, OF SPRINGFIELD, MASSACHUSETTS, ASSIGNOR TO J. STEVENS ARMS & TOOL COMPANY, OF CHICOPEE FALLS, MASSACHUSETTS, A CORPORATION OF MASSACHUSETTS.

REBOUNDING HAMMER.

1,070,145.

Specification of Letters Patent. Patented Aug. 12, 1913.

Application filed January 21, 1913. Serial No. 743,265.

To all whom it may concern:

Be it known that I, GEORGE S. LEWIS, a citizen of the United States, residing in Springfield, Hampden county, State of Massachusetts, have invented certain new and useful Improvements in Rebounding Hammers, of which the following is a specification, reference being had to the accompanying drawings, which form a part hereof.

10 This invention relates to rebounding hammers designed primarily with reference to their use in single-shot firearms of low cost.

It has for an object to provide an efficient rebounding hammer which shall not be 15 unduly heavy and which shall operate with unvarying certainty to explode the cartridge.

It has for a further object to improve generally the construction of such devices and 20 to eliminate certain undesirable features which have appeared in prior constructions.

In the usual arrangement, with a coiled main spring, the spring plunger acts on a pin on one side of the hammer pivot to 25 throw the hammer down, and during the last part of the travel of the latter acts on a pin on the other side of the hammer pivot to cause the hammer to rebound. In this construction the hammer, at the end of its 30 stroke, moves against the tension of the main spring and so the force of the blow is reduced and often insufficient to explode the cartridge. In accordance with the present invention this disadvantage is removed by 35 having the hammer relieved of the action of the spring plunger during the latter part of its stroke and continue its movement solely by its own momentum. The rebound of the hammer is then effected by suitable 40 means independent of the main spring.

The invention will be described more particularly with reference to the accompanying drawings in which—

Figure 1 is a fragmentary view partly in 45 section of a firearm provided with a hammer constructed in accordance with the invention, the hammer being shown in full lines in cocked position. Fig. 2 is a similar view showing the hammer half-cocked.

50 The gun herein illustrated comprises a frame *a* and barrel *b* of usual construction with a hammer *c* pivotally mounted as at *d* in the frame and in operative relation with respect to the usual firing pin *a'*. The gen-

eral configuration of the hammer *c* is unchanged in the present invention, the usual half cock notch *c'* and full cock notch *c''* being provided to coöperate with the combined sear and trigger *e* which is engaged by a leaf spring *f* secured to the gun frame 55 by a screw *f'*. The rear face of the hammer *c* is notched as at *c³* to receive and guide the coiled main spring and spring plunger *g*. The construction thus far set forth is known in the art, and the foregoing 60 description it is believed, is sufficient for a clear understanding of the particular improvements which constitute the subject matter of this invention and which will now be described. The head *g'* of the spring 65 plunger *g* has its upper forward edge in engagement with the notch *c³* of the hammer *c* while the under face of the head *g'* is slotted as at *g²* to straddle the hammer. The vertical edges of the head *g'* adjacent 70 the slot *g²* are formed to engage the pivot pin *d* at a predetermined time with respect to the travel of the hammer *c* to limit positively further movement of the spring 75 plunger *g*. To prevent a sliding movement 80 of the head *g'* on the pivot pin *d* the vertical edges of the head *g'* are preferably concaved as indicated in dotted lines in Fig. 2. As appears in the same figure, the engagement of the forward edges of the head *g'* with 85 the pivot pin *d* may, and preferably does, occur at about the time that the hammer is in its normal half-cocked position. The throw of the hammer *c* after it is relieved from the action of the spring plunger *g* in 90 the manner indicated above, continues solely by its own momentum. The rebound of the hammer after the cartridge has exploded is brought about by the engagement of the 95 sear with a cam surface *c⁴* formed on the hammer *c* at a point just above the half-cock notch *c'*. This movement, it will be understood, is initiated by the leaf spring *f* acting on the trigger *e*.

In operation, the hammer is retracted 100 against the tension of the main spring until the sear engages the full cock notch *c''* when the parts assume the position indicated in Fig. 1. When the trigger is pressed so as to disengage the sear and the hammer, the 105 latter is thrown forward under the influence of the spring plunger *g*. The effective action of the latter on the hammer continues

- until the forward edges of the head g' engage the pivot pin d when the hammer continues its forward movement solely under its own momentum. The last portion of the travel of the hammer accordingly is not attended with a counteraction on the part of the main spring or auxiliary springs as in previous constructions and the force of the hammer accordingly remains undiminished.
- 10 After the delivery of the blow of the hammer on the firing pin, the trigger is relieved from the pressure of the finger so that the spring f is free to move the sear along the cam surface c^4 with a force sufficient to rock the hammer rearwardly until the sear enters the half-cock notch c' . This rearward movement of the hammer, which in practice amounts to a rebound of the same, is perfectly free, since the spring plunger g is held
- 15 in its arrested position by the pivot pin d .
- I claim as my invention:
1. In a firearm, the combination of a frame, a hammer pivotally mounted therein and a spring plunger in operative engagement therewith and having a slotted head to straddle the same, the hammer pivot being disposed in the path of the plunger head to
- 20
- 25

arrest the movement of the plunger during the throw of the hammer.

2. In a firearm the combination of a frame, a hammer pivotally mounted therein, a spring plunger in operative engagement therewith having a slotted head to straddle the same, the hammer pivot being disposed in the path of the plunger head to arrest the movement of the plunger during the throw of the hammer, and means to move the hammer to half-cocked position after firing.

3. In a firearm the combination of a frame, a hammer pivotally mounted therein, a spring plunger in operative engagement therewith having a slotted head to straddle the same, the hammer pivot being disposed in the path of the plunger head to arrest the movement of the plunger during the throw of the hammer, and a spring pressed sear to coöperate with said hammer to move the same to half-cocked position after firing.

This specification signed and witnessed this 16th day of January A. D., 1913.

GEORGE S. LEWIS.
